(57) **CLAIM**

The ornamental design for a drywall anchor, as shown and described.

DESCRIPTION

FIG. 1 is a top, front, left perspective view of a drywall anchor;

FIG. 2 is a bottom, back, right perspective view

FIG. 3 is a left side view thereof.

FIG. 4 is a right side view thereof.

FIG. 5 is a front side view thereof.

FIG. 6 is a back side view thereof.

FIG. 7 is a top view thereof; and,

FIG. 8 is a bottom view thereof.

1 Claim, 7 Drawing Sheets
